AUGUSTINE WALTER WELCH, OF PHILADELPHIA, PENNSYLVANIA, ASSIGNOR TO COLUMBIA SALVAGE CORPORATION, OF NEW YORK, N. Y., A CORPORATION OF NEW YORK.

METHOD AND APPARATUS FOR REMOVING PRIMERS FROM ARTILLERY CARTRIDGE CASINGS.

Application filed November 10, 1924. Serial No. 748,914.

To all whom it may concern:

Be it known that I, AUGUSTINE WALTER WELCH, a citizen of the United States, and resident of Philadelphia, in the county of 5 Philadelphia and State of Pennsylvania, have invented certain new and useful Improvements in Methods and Apparatus for Removing Primers from Artillery Cartridge Casings (Case No. 16), of which the following is a specification.

This invention relates to the salvaging of artillery ammunition and has for an object to perform a step in the salvaging operations with ease, quickness and safety.

15 A further object is the provision of a simple, efficient and easily operated apparatus for detonating the primer charge of a propelling charge case for artillery ammunition and driving the primer shell from the 20 end of the case. The case is thereby rendered in condition to have further salvaging operations performed thereon.

In the drawings,

Fig. 1 is a vertical central section through 25 the primer removing apparatus;

Fig. 2 a front elevation thereof; and

Fig. 3 an enlarged detail section showing the primer alined with the punch in preparation for the punching operation thereon.

30 Referring to the parts of the apparatus by numerals, 1 designates the main frame, formed with the spaced side members 2. The side members 2 are connected by a bridge or table 3 and a pair of spaced standards 4 extend upwardly from the table 3 and have a shaft 5 journaled in their upper ends. The shaft 5 is formed with a crank 6 between the upper ends of the standards and said crank is connected by means of a 35 connecting rod 7 with a cross-head 8 that is adapted to reciprocate vertically between guides 9 carried by the standards 4. The lower end of the cross-head 8 carries a socket member 10 at its lower end and is movably secured in the socket by means of a set screw 11 is a downwardly extending punch 12. The lower end of the punch 12, is guided by a bushing 13 that is fitted 45 within an aperture in the table 3.

50 A rock shaft 14 extends between the side members 2 of the frame and carries reduced stub shafts 15 at its opposite ends which are

journaled in the side members. The rock shaft 14 is formed with a recess 15' in one side and intermediate its ends, and in this recess is fitted the lower end of an upwardly extending tubular cartridge casing support 16. The tube 16 is secured to the rock shaft by means of a U-shaped clip 17, the shanks of which pass through the shaft and have 60 nuts 18 threaded on their outer ends. One of the stub shafts 15 on the rock shaft extends outwardly of the frame 1 and has a foot lever fixed thereto. The foot lever is formed with a treadle arm 19 extending 65 forwardly from the shaft and with an arm 20 extending rearwardly from the shaft and carrying a weight 21.

The punch is power operated through a belt which runs over a pulley 22. This pulley is normally disconnected from the punch operating shaft 5, but is adapted to be connected thereto by a clutch 23 which may be of any suitable form. The treadle arm 19 of the foot lever is operatively connected to 75 the clutch through the means of a reach rod 24 and a clutch shipping lever 25.

In the operation of the apparatus the operator steps upon the treadle 19 to rock the shaft 14 and swing the tube 16 forwardly to 80 receive a cartridge casing, as shown in dotted lines in Fig. 1. A cartridge casing C, from which the explosive charge has been removed, is telescoped over the tube 16. The cartridge casing still contains the primer P 85 and when the casing is placed upon the tube 17 the upper end of the tube bottoms against the base of the casing and surrounds the inwardly extending primer. The operator next releases the treadle 19 and the 90 rock shaft is turned by the weight 21 to automatically swing the tube 16 and cartridge casing to an upright position. The cartridge casing is accurately stopped in alignment with the punch by an adjustable stop screw 26 threaded through a lug which depends from the table 3. As the cartridge casing is swung into alignment with the punch, the upward movement of the treadle 19 operates the clutch through the connections 24 and 25 and the punch is caused to descend. The lower end of the punch is reduced as at 27 to form a firing pin, and as the punch descends the firing pin first 100

strikes and detonates the primer charge; next, the shouldered portion 28 of the punch surrounding the firing pin strikes the primer shell and drives it out of the base of the 5 cartridge casing and down through the tube 16. The tube 16 is open at its lower end and communicates with a tubular discharge chute 29 into which the primer shell is delivered. As the punch is retracted the 10 operator again steps upon the treadle to disconnect the clutch and swing the tube 16 forward in order to remove the cartridge casing therefrom.

The cartridge casing shown is of the 15 standard type used for containing the propelling charge for a shrapnel shell. The shrapnel shell is first removed from the end of the casing and next the propelling charge is removed. The casing is formed of brass 20 and the primer shell of another metal and the removal of the primer shell and its explosive charge from the casing renders the casing in condition to be cast into a reduction furnace or to have other salvaging 25 operations performed thereon with safety. Owing to the fact that the primer charge is detonated within the tube 16 and that the tube extends below the cartridge casing and delivers directly into the discharge 30 chute, the operator is protected from danger and from the fumes of the explosion and also the fire risk is greatly reduced. This is an important consideration when explosives are near by. The tube 16 also 35 protects the walls of the casing from dirt and soot and from the fumes of mercury which result from the explosion of the primer charge and which would have a bad effect upon the brass of the casing. The explosion furthermore makes considerably less noise within the tube than if it occurred directly within the casing and set the walls thereof in vibration. Still another advantage in the use of the tube is that it 40 serves as a means to quickly test the casing to make sure that the propelling charge has been entirely removed therefrom and that it is safe to explode the primer charge. If the casing bottoms upon the upper end 45 of the tube when it is placed thereover, it indicates that the casing is empty.

It will be seen from the foregoing that the machine is well adapted to perform its 50 operation with quickness and safety and without injury to the material to be salvaged. It is possible by the use of the machine to operate upon large quantities of work safely and profitably and without the employment of skilled or specially trained 55 labor.

What I claim is:

1. A device of the class described comprising a punch, a cartridge casing support adapted to be shifted to move the shell into 60 and out of alinement with the punch, and

means to cause the automatic operation of the punch to detonate the primer charge and force the primer shell from the cartridge casing when the casing is moved into alinement with the punch. 70

2. A device of the class described comprising a punch, a tubular cartridge casing support adapted to extend within the cartridge casing and surround the primer, and means to operate the punch to detonate 75 the primer charge and force the primer shell from the cartridge casing. 75

3. A device of the class described comprising a punch, a cartridge casing support adapted to be shifted by the operator 80 out of alinement with the punch, means to automatically return the support with a cartridge casing thereon into alinement with the punch, and means operated by said support returning means to automatically 85 cause the punch to operate to detonate the primer charge and drive the primer shell from the cartridge casing when said casing is moved into alinement with the punch. 90

4. A device of the class described comprising a punch, a rockable cartridge casing support adapted to be rocked to carry the cartridge casing into and out of alinement with the punch, and means to cause the punch to operate when the casing is in 95 alinement therewith to detonate the primer charge and drive the primer shell from the casing. 95

5. A device of the class described comprising a punch, a shiftable cartridge casing support in the form of a tube adapted to extend within the cartridge casing and enclose the primer, and means to operate the 100 punch to detonate the primer charge within said tube and drive the primer shell from the cartridge casing and through the tube. 105

6. A device of the class described comprising a punch, a rock shaft, a cartridge casing support carried by the rock shaft and adapted to support the casing in alinement with the punch, means to rock the 110 said shaft to shift the support and casing out of alinement with the punch, and means connected with the shaft rocking means and operable by the movement thereof to cause 115 the punch to operate to detonate the primer charge and drive the primer shell from the cartridge casing. 115

7. A device of the class described comprising a punch, a rockably mounted cartridge casing support in the form of a tube open at both ends and adapted to extend into the cartridge casing and enclose the primer, means to rock the support and the cartridge casing into and out of alinement 120 with the punch, and means to cause the punch to operate to detonate the primer charge within the supporting tube and drive the primer shell from the cartridge casing 125 and through the tube. 130

8. A device of the class described comprising a punch, a rockable cartridge casing support, a pedal adapted for rocking said support out of alinement with the punch 5 to receive the cartridge casing, means to automatically rock the support and casing into alinement with the punch when the pedal is released, and means connected with said automatic support rocking means to 10 cause the punch to automatically operate when the cartridge casing is rocked into alinement therewith to detonate the primer charge and force the primer shell from the cartridge casing.
- 15 9. The method of removing the primer from an artillery cartridge casing consist-

ing in placing the cartridge casing over an open ended tubular support with the tube enclosing the primer charge at the inner side of the closed end of the casing and extending out through the open end of the casing, placing said support and casing with the primer in alinement with a mechanically operated punch, and causing 20 said punch to detonate the primer charge 25 within the tube and force the primer shell from the cartridge casing and through the tube in one punching operation.

In testimony whereof I hereunto affix my signature.

AUGUSTINE WALTER WELCH.
